UNITED STATES PATENT OFFICE.

JOSEPH W. LEWIS, JR., OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

METHOD OF AND APPARATUS FOR TREATING PETROLEUM.

Application filed April 4, 1925. Serial No. 20,638.

My invention relates to a method of and apparatus for converting hydro-carbons or mineral oils into lighter oils or oils of lower boiling points; and more particularly my invention relates to a method of and apparatus for subjecting petroleum, petroleum distillate or petroleum residuum to conditions of temperature and super-atmospheric pressure to effect destructive distillation, dissociation or cracking of the oil for the production of light hydrocarbons such as napthas, gasolines and burning or kerosene oil.

This application is in part a continuation of my prior application Serial No. 601,220, filed November 16, 1922.

In the well-known and commonly used cracking processes one of the principal sources of trouble is in the deposition and accumulation of carbon and carbonaceous matter on the heating surfaces thereby cutting down the rate of heat transfer and, if permitted to continue, eventually rendering the apparatus inoperative. In accordance with my invention, the velocity of the oil over the heating surfaces is high thereby increasing the rate of heat transfer to the oil and also largely preventing the deposition of any carbon or carbonaceous matter which may be formed. My method is accordingly characterized by high rate of heat transfer into the oil and by high velocity of the oil over the heating surface, the oil and conversion products preferably remaining wholly or largely in the liquid phase.

To effect the high rate of transfer of heat energy into the oil and to prevent local super-heating, the oil is caused to flow in a helical or equivalent path within a tube through whose wall the heat is transferred into the oil flowing in a stream of reduced cross section, in contact with the inner surface of the tube wall, the passage through the helical or equivalent path serving also to stir and intermingle all portions of the oil and to bring them into substantially direct heat transfer relation with the inner surface of the tube wall and with the helix surfaces.

The helical path also serves by its smaller cross section to impart a high velocity to the

oil which substantially prevents the deposition from it of carbon or carbonaceous matter on the heating surface. The heat transfer is increased by the helical path both because of the increased velocity of the oil over the heating surface and because of additional heat actually conducted into the oil and transferred to it by the helix itself.

In accordance with my invention, the oil may be heated to a higher temperature than is normally used and the time of the cracking reaction in the tubes may be thereby decreased. When such high temperatures are used, it is, of course, necessary to employ correspondingly high pressures, particularly on the lighter or lower boiling oils charged or produced, to maintain the oil substantially in the liquid phase. It is possible by means of my invention to obtain relatively high conversions from high to low boiling products in a brief cracking period with the deposition of very little carbon on the heating surfaces and with low gas loss.

Further in accordance with my invention there may be utilized a reaction chamber in which the oil is retained while at cracking temperature and in which the major portion or substantially all of the cracking takes place after the oil has been heated in the aforesaid helical or equivalent path, in which the heat transfer is so increased and the time of heating, therefore, so decreased that the oil may be heated to a higher temperature than is otherwise possible without any substantial cracking taking place in the tubes. The high velocity of the oil in the tubes at the same time substantially prevents the deposition on the heating surfaces of the small amount of carbon which is formed, thereby avoiding necessity of cleaning the tubes except at infrequent intervals, and so permitting longer runs, and, at the same time, procuring more efficient cracking because of the higher permissible temperature.

Though my invention is not limited thereto, an application of it will be described hereinafter from the standpoint of the cracking of gas oil or fuel oil under pressure for the production of gasolines and the like,

though it will be understood that oils lighter or heavier than gas oil or fuel oil may be treated in accordance with my invention for producing oils of lower boiling points.

5 For an understanding of some of the modes of practicing my method and for an illustration of some of the forms my apparatus may take, reference is to be had to the accompanying drawings, in which:

10 Fig. 1 is a vertical sectional view, some parts in elevation, of apparatus embodying my invention.

Fig. 2 is a plan view of structure of the character illustrated in Fig. 1.

Fig. 3 is a longitudinal sectional view, parts in elevation, showing an oil cracking tube and the helix member within the same.

Fig. 4 is a fragmentary view illustrating structure of the cooler or condenser.

20 Fig. 5 is a flow sheet or chart.

Fig. 6 is a vertical sectional view, some parts in elevation, of a modified form of apparatus.

Referring to Figs. 1-4, F is a furnace or combustion chamber in which gas, oil or other fuel is burned, a blower B driven by motor M being utilized, if suitable or desirable, for supplying air and inducing draft. The hot gases pass from the furnace F through the flue *a* into the manifold tunnel or flue A, common to and extending in front of the ends of the several tubular cracking stills or units S, ten in number in the example illustrated in Fig. 2.

35 Each still structure comprises enclosing and surrounding brickwork *b* and interior walls or partitions *c*, of brickwork or the like, forming flues or hot gas passages *d* communicating with each other at opposite 40 ends of the structure and forming a continuous passage. Hot gases from the tunnel A are delivered into the lowermost flue passage *d* through the flue *e*, controllable by the damper *f*. The gases flow to the right, Fig. 45 1, through the lowermost flue passage *d*, thence toward the left to the middle flue passage *d*, and thence toward the right through the upper flue passage *d*, and thence through the flue passage *g*, controllable by the damper 50 *h*, to the manifold discharge flue C, controllable by the damper *i*, to the chimney or stack D.

55 Extending through each of the flue passages d is a cracking tube T , there being preferably a single tube T for each flue passage d , though it will be understood that two or more tubes T may be employed in each flue passage. While the tubes T are shown as disposed horizontally, it will be understood that they may be disposed vertically or in any suitable inclined position. Each of the tubes T terminates in the end chambers j and k , isolated by the end walls b , b from communication 60 with the flue passages d . Threaded on each 65

end of each tube T is a coupling flange m abutting against similar flanges n on the pipe members or bends o , bolts p serving to draw the flanges m and n snugly together to form a pressure-tight joint between the tubes T and the pipe sections o , which latter serve to connect the several tubes T in series with each other. In the connections o may be provided blocks q for reception of pyrometers, or other suitable temperature-measuring devices.

Within each tube T and extending throughout its length, particularly that part of its length disposed in the heating zone, is disposed the helix member or structure H , fitting fairly snugly within the tube T and bearing thereon at the periphery of the threads or helical ribs, the core r being provided at either or both ends, as at s , with a squared end for reception of a wrench or the like for rotating the helix structure H when the apparatus is not in operation for loosening such small deposits of coke, carbon or carbonaceous material as may adhere to the inner wall of the tube T . By uncoupling the pipe sections o from a tube T , the helix structure may be withdrawn from the tube T , cleaned and reintroduced, or a clean spare helix H may be immediately introduced.

In a receiving or pump house E is disposed a pump P, of any suitable type, to which the oil to be converted or treated is delivered through the pipe *t*, raised in pressure, and delivered to the manifold *u*, with which communicate the oil supply pipes *v*, one for each still unit, a meter *w* and a valve *x* being disposed in each of the pipes *v*. 100

Each pipe v delivers the oil, under pressure corresponding with the pressure utilized within the tubes T , to the heat exchange structure G , of any suitable character. In the example illustrated, it comprises a tube into which the pipe v delivers and through which extends the tube y , connected through the valve z with the discharge end of the series of tubes T . The tube y is traversed by hot oil, from which heat is transferred to the incoming oil surrounding the tube y , whereby the incoming oil is preheated, as for example, to 550 degrees F., and discharged from the heat exchange apparatus through the valve a^1 to the pipe b^1 , which connects with the inlet end of the tube system b , which connects with the pipe v .

tem at the left end of the lower tube T , Fig. 1. The oil, after traversing the tubes T , is delivered from the tube y through the valve c^1 to the manually adjustable pressure-regulating or automatic pressure-reducing valve V , which delivers the oil to the pipe d^1 and thence to the coil or worm I of a cooler or condenser J through which cooling medium, as water, is circulated, the same entering, for example, at e^1 and discharging at f^1 .

The coil or worm I comprises lengths of tube or piping extending through the wall 13

of the box or tank J and connected in series with each other on the exterior thereof by the return bends or couplings g^1 , Fig. 4, which are removable, so that from the exterior of the cooler or condenser the interior of the tubes may be accessible for cleaning therefrom carbonaceous or other deposits.

The several worms or pipe coils I of the different still units may be disposed within one and the same box or tank J, as indicated in Fig. 2. The discharge outlet of each worm or coil I is connected through a pipe k^1 and a strainer i^1 with a receiving drum or tank R, in which the permanent or uncondensable gas and liquid oil separate from each other, the gas being drawn off through the valve j^1 and pipe k^1 to the gas manifold pipe K, which delivers into any suitable gas storage tank. When the cooler or condenser coil or worm I and drum R are under super-atmospheric pressure, there may be employed the pressure-reducing valve N, which delivers the gas to the pipe k^1 at atmospheric or slightly super-atmospheric pressure. Connecting with each pipe k^1 may be provided a pipe m^1 , controlled by a valve n^1 , for venting the pipe k^1 to atmosphere.

The oil is discharged from the receiver or drum R through a meter o^1 and a liquid-delivering trap or valve structure p^1 , which delivers the oil at lower pressure, if super-atmospheric pressure exists upon the drum R, through the pipe q^1 , controlled by valve r^1 , to the manifold pipe L, which delivers to storage tank O, or any other suitable destination, as for example, the fire stills hereinafter referred to in connection with Fig. 5. The meter o^1 and trap p^1 may be by-passed through the valve s^1 , a valve t^1 intervening between the trap p^1 and the by-pass.

Extending across the several stills or pressure tube units is a platform or walk Q, for convenience of the attendants.

Running adjacent the walk Q is a pipe U, communicating with a steam boiler for delivering steam for purposes of cleaning the pressure tube structure. Connection is made to the pipe U for each tube unit through a valve u^1 and a check valve v^1 with the pipe b^1 , whereby steam may be passed through the pipe b^1 and through the tubes T for blowing them out or cleaning them either before or after removal of the helix structures H, the check valve v^1 preventing flow of vapors or oil to the steam pipe U when the pressure employed upon the tubes T during their operation is greater than that of the steam supplied to the pipe U.

The aforesaid cracking tubes T may be of any suitable material to withstand the pressures and temperatures involved as herein described, and may be, for example, of

annealed drawn seamless steel tubing having about .5 per cent carbon.

By way of example of apparatus which I have successfully employed in accordance with my invention, it may be stated that the internal diameter of each tube T is two inches and its external diameter about 2.375 inches, each tube having a length of about twenty feet, of which about seventeen and a half feet are disposed within the heating zone or flue d , whose cross section may vary from about six inches to about fifteen inches square. The cylindrical core r of the helix structure H is about one inch in diameter and the thickness of the thread about one-quarter inch, whereby the cross section of the helical path for the oil is about one-half inch deep and three-quarters inch wide, the area of the cross section being approximately three-eighths of a square inch, or about one-eighth of the cross section of the tube. The pitch of the helix is about one inch, whereby for each linear foot of the tube T the oil makes twelve turns around the core r . Any suitable number of tubes T in series or tandem may be utilized, and the rate of delivery of the oil to be treated is preferably such that the time required for the oil to traverse the tubes will be of the order of five to twenty-five minutes, and a period of ten minutes is found suitable when using three of the above mentioned tubes having a length of about twenty feet with about seventeen and one-half feet within the heating zone. With the aforesaid rate of delivery of oil to be treated into the cracking tubes, there is effected, because of the helical path and its small cross section, a velocity sufficient to prevent deposition of substantial quantities of carbon or carbonaceous material upon the heating surfaces. However, by utilizing more tubes in series or tandem, thereby increasing the length of the helical path, the velocity of flow is correspondingly higher, when an equal quantity of oil is pumped through in the same total time of passage, thereby increasing the rate of heat transfer.

The pressure maintained upon the oil while traversing the cracking tubes may range from about 200 to about 2000 pounds per square inch, and is effected largely or substantially entirely by the pump P.

The hot gases entering the left end of the lowermost flue passage d have a temperature of the order of 2000 degrees F. and at their discharge at the entrance to the flue g have a temperature of the order of 1000 degrees F. The oil entering the system of tubes T will have a temperature of the order of 550 degrees, and at the discharge end of the tubes T will have a temperature of the order of 1000 degrees F., the temperature of the oil dropping materially in the heat exchange

structure G in raising the incoming oil to the aforesaid temperature of about 550 degrees F. However, temperatures of the order of 750 degrees to 1050 degrees may be attained by the oil before leaving the tube structure T.

It will be noted that the hot gases and the oil in this example flow in the same direction through the flue passages d and the tubes T therein. It shall be understood, however, that my invention is not limited to concurrent flow, but that the hot gases may flow in direction counter to that of the oil in the tubes, or that the gases may be caused to flow throughout a part of their path in the same direction with the oil and in another part of the path in opposite direction thereto.

When operating under my method as above described, only very small quantities of carbon or carbonaceous materials are formed. In a continuous run of about four days duration the carbon produced weighed as little as .05 per cent of the weight of the oil discharged from the drum R.

The treated oil obtained by the use of my invention may subsequently be treated in any suitable or desirable way, such as by fractional distillation, yielding distillates of gasoline and naptha, lamp oil and gas oil, leaving as bottoms fuel oil or heavy lubricating stock, as indicated, for example, in Fig. 5. The various distillates may be chemically or physically treated in any of the well known ways to yield standard products.

The utilization of the helical path of the type above described is further of advantage in a system of the character indicated in Fig. 6, wherein the oil is first heated for a relatively short period during traverse of the helical path at velocity higher than in the system of Fig. 1 and in liquid phase to raise it to suitably high temperature, without substantial cracking, and then discharged into the reaction chamber Z, preferably heat-insulated, and of suitably large dimensions to retain a large bulk of liquid oil, where the major portion or substantially all of the cracking is effected during the prolonged period during which the oil remains in that chamber at suitable cracking temperature, the high pressure obtaining in the tubes, or suitably lower super-atmospheric pressure, being maintained in the reaction chamber.

In this case, the rate of combustion in the furnace F may be suitably higher than in the system of Fig. 1 to enhance rapidity of heating the oil in traversing the helical path and preferably also to cause it to attain a relatively higher temperature upon discharge from the tubes to the reaction chamber Z.

In the example indicated in Fig. 6, the oil to be treated is introduced, either cold or

previously heated, under pressure by a suitable pump, corresponding with pump P of Fig. 1, at a^2 , into the tube system from which it is discharged through the line b^2 to the reaction chamber Z.

The oil remains for a substantial period in the reaction chamber Z, for example, twenty minutes, and is discharged through the pressure-reducing valve c^2 , together with some vapors, into the vaporizing chamber or fractionating tower d^2 , in which there may obtain substantially atmospheric pressure or preferably a super-atmospheric pressure, for example, forty pounds per square inch. From the upper portion of the tower d^2 there are drawn off through the line e^2 certain vapors, comprising the lighter conversion products and some unconverted oil or comprising lighter conversion products only, and delivered to the cooling worm f^2 of the water-cooled condenser g^2 . The condensate is then delivered to the receiving drum R, wherein the gas is separated from the condensate, the gas being drawn off through the line h^2 and the condensate through the line i^2 , the condensate then being further refined, as by distillation of the general character indicated in Fig. 5.

In the bottom of the vaporizing or fractionating tower d^2 is collected the unvaporized portion of the material discharged from the reaction chamber Z. This material is of the character of tar or fuel oil, which is discharged through the worm j^2 of the tar cooler k^2 .

In a system of the character described in connection with Fig. 6, the rate of transfer of heat into the charged oil in the tubes T is high, and the period of heating relatively short, with no or at most only small amount of cracking of the oil during traverse of the heating tubes. Furthermore, the velocity of the oil through the helical path is sufficiently high to afford insufficient time for cracking and to ensure that such small quantities of carbon or carbonaceous material as may be formed are not to substantial degree deposited upon the heating surfaces. Furthermore, in accordance with this method, higher oil temperatures are permissible in the tubes, procuring more efficient cracking upon reaching the reaction chamber Z.

When the capacity of a reaction chamber Z is sufficiently large, a plurality of heating tube units, arranged for example in general as indicated in Fig. 2, may be simultaneously employed to heat the oil in separate streams and discharge them to the reaction chamber.

The foregoing method as described in connection with the use of the reaction chamber is preferred, though it will be understood that other modes of use of reaction chamber may be practiced. For example, a lower pressure may be used upon the tube structure T and within the reaction chamber, in

which event vaporization may take place in that chamber, and the vapors drawn off therefrom for condensation, and there may be drawn off from the reaction chamber tar 5 or other carbonaceous residuum.

What I claim is:

1. The method of producing lower boiling point from higher boiling point hydrocarbon oils, which comprises passing the higher boiling point oil in liquid phase in a helical path through a tubular passage in a stream whose cross section is a small fraction of the cross section of said tubular passage, and subjecting the oil while in said helical path to cracking temperature.

2. A tubular pressure cracking still structure comprising a tube, a stationary helix member therein, said helix member having such pitch and having a core of such diameter that the cross section of the helical path is a small fraction of the cross section of said tube, means for forcing oil in liquid phase through said helical path, and heater structure surrounding said tube.

25 3. In the art of producing lower boiling point from higher boiling point hydrocarbon

oils the method which comprises rapidly passing the higher boiling point oil in liquid phase while under super-atmospheric pressure once through a heating zone in a helical path through a tubular passage in a stream whose cross section is a small fraction of the cross section of said tubular passage, subjecting the oil while in said helical path to cracking temperature, thereafter delivering the hot oil into a cracking zone, and effecting the major portion of the cracking in said cracking zone.

4. Still structure for cracking hydrocarbon oils comprising a tube, a stationary helix member therein, said helix member having such pitch and having a core of such diameter that the cross section of the helical path is a small fraction of the cross section of said tube, means for forcing the oil in liquid phase under super-atmospheric pressure through said helical path, heating structure surrounding said tube, and a cracking chamber to which the heated oil is delivered from said helical path.

JOSEPH W. LEWIS, JR.
